PAUL CRICCHIO, OF NEW YORK, N. Y., ASSIGNOR TO MAJESTIC LAMP WORKS, OF NEW YORK, N. Y., A PARTNERSHIP OF PHILIP SILBERHARTZ, JACOB SILBERHARTZ, AND HARRY SCHEINER, ALL OF BROOKLYN, NEW YORK

DESIGN FOR A HANDLE FOR SMOKERS' STANDS OR ARTICLES OF ANALOGOUS NATURE

Application filed August 2, 1929. Serial No. 32,287. Term of patent 3½ years.

To all whom it may concern:

Be it known that I PAUL CRICCHIO, a citizen of the United States, and a resident of New York, county of Bronx, and State of New York, have invented a new, original, and ornamental design for a Handle for Smokers' Stands or Articles of Analogous Nature, of which the following is a specification, reference being had to the drawing, forming a part thereof.

In the drawing:

Figure 1 is an elevational view of either side of the handle for smokers' stands or articles of analogous nature; and

I claim:

The ornamental design for a handle for smokers' stands or articles of analogous nature substantially as shown.

PAUL CRICCHIO.
